Attorney

UNITED STATES PATENT OFFICE.

WILLIAM BROWNLIE, OF LONG ISLAND CITY, NEW YORK.

WIND AND WATER EXCLUDER.

Application filed February 11, 1924. Serial No. 692,046.

To all whom it may concern:

Be it known that I, WILLIAM BROWNLIE, a citizen of Great Britain, residing at Long Island City, in the county of Queens and 5 State of New York, have invented a new and useful Wind and Water Excluder, of which the following is a specification.

This invention relates to weather strips for doors and windows.

10 The object of the invention is to provide a device of this character carried by a closure such as a door or window which is so constructed as to normally tilt into inoperative position on the opening of the 15 closure and to be forced into sealing position when the closure is closed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed without departing from the spirit of the invention.

In the accompanying drawings:—

Figure 1 represents a front elevation of the lower portion of a door and its frame 20 with this improved device shown applied and in operative position; and

Fig. 2 is a transverse section taken on the line 2—2 of Fig. 1.

In the embodiment illustrated a door sill 35 1 is shown from the ends of which rise the door frame 2 having stiles 3 secured to the inner faces thereof, said stiles being cut away at their outer rear corners as shown at 4 to receive a molding 10 carried by the closure 15 which may be either a door or a window.

Secured to the lower end of the inner face of one of the stiles 3 is a striking post 11 the lower end of which is beveled as 45 shown at 12 for a purpose to be described.

A metal strip or bar 13 is secured to the sill 1 midway the width thereof and is preferably semi-circular in cross section as shown clearly in Fig. 2.

50 The molding 10 carried by the closure 15 inclines downwardly and forwardly and has its inner face at its lower portion recessed as shown at 14 to form a housing for the sealing member 16. This molding termi-

nates above the lower edge of the closure and 55 the sealing plate 16 fills the space between the molding and said closure bottom.

This sealing plate 16 is made wedge-shaped in cross section with the thicker portion 17 thereof located in the recess 14 of 60 the molding, the thin front edge projecting beyond the molding and beveled as shown at 18 to fit flat against the door sill when the closure is closed as shown in Fig. 2.

65 This plate 16 is pivotally mounted on brackets as 19 any desired number of which may be employed according to the size of the closure and the plate 16 to be supported thereby. Each of these brackets 19 is

70 L-shaped in form with the long arm 20 thereof arranged flat against the front face of the closure 15 between it and the molding 10 and which is secured in place by a screw 21 extending through the molding and the bracket and entering the closure, the head of the screw being preferably countersunk. The short arm 22 of the bracket extends forwardly below the molding 10 and has its 75 terminal 23 bent upwardly and outwardly 80 to form a pintle for plate 16.

85 The plate 16 being mounted as above described with its thickened heavier portion housed within the recess 14 of the molding will normally swing with its front edge into 90 raised or open position, said swinging movement being controlled by the engagement of the rear edge of the plate with the arms 20 of the brackets.

95 It will thus be seen that when the closure is swung outwardly into open position the sealing plate 16 will automatically raise to clear the sill. When the door is closed the lower or front edge of plate 16 will ride up over the rounded bar 13 and on entering the recess 4 in the stile will be engaged by the beveled end of the striking post 11 which will force said plate downwardly into tight closed position and hold it in this position preventing all possibility of water or air entering 100 under it.

105 A closure equipped with this improved weather strip will effectively shut out air and water and the strip will last indefinitely owing to the fact that the sealing member and the striking post which receive the greater portion of the wear are made of metal.

I claim:—

1. The combination with a closure; of a molding mounted on the outer face of the closure near one edge thereof with its lower edge inclined outwardly, L-shaped metal brackets having one arm mounted between said molding and said closure and attached by screws passing through the molding, said arms and into the closure, the other arm of the bracket extending laterally outward, a metal plate arranged under this molding, said plate being wedge-shaped in cross section and its thin lower edge beveled to fit snugly against the frame of the closure, said plate being apertured midway its width and pivotally mounted on said bracket ends, the thick portion of the plate being adapted to cause the plate to swing downwardly at said weighted end and raise its lower end, and a metal striking post having a beveled end located in the path of said plate to force it downward into closed position on the closing of the closure.
2. The combination with a closure; L-shaped brackets secured to the outer face of said closure near one edge thereof and having one arm projecting laterally outward, said arm having upturned obliquely disposed terminals to form pivots, a flat metal sealing plate wedge-shaped in cross section pivotally mounted intermediate its width on said obliquely disposed bracket ends, with the weighted edge of said plate disposed upwardly whereby the lower edge is normally swung upwardly and outwardly, and a metal striking post having a beveled lower edge located in the path of said plate to force it into closed position on the closing of the closure.
3. The combination with a closure; of a molding mounted on the outer face of the closure near one edge thereof with its lower edge inclined outwardly and provided on its inner face adjacent said edge with a recess, L-shaped metal brackets having one arm mounted between said molding and said closure and attached by screws passing through the molding, said arm and into the closure, the other arm of the brackets extending laterally outward and having upturned obliquely disposed terminals to form pivots, a metal plate arranged under said molding said plate being wedge-shaped in cross section and its thin lower edge beveled to fit snugly against the frame of the closure, said plate being apertured midway its width and pivotally mounted on said obliquely disposed bracket ends, the thick portion of the plate being movable into said recess in the closed position of the closure and adapted to cause said end of the plate to swing downwardly and raise the thin edge when the closure is in open position, and a metal striking post having a beveled lower end located in the path of said plate to force the thin edge downward into closed position on the closing of the closure.

In testimony that I claim the foregoing as my own, I have hereto affixed my signature in the presence of two witnesses.

WILLIAM BROWNLIE.
